ALFRED SCHWARZ, OF NEW YORK, N. Y., ASSIGNOR TO SCHWARZ
ENGINEERING COMPANY, OF NEW YORK, N. Y., A CORPORA-
TION OF NEW YORK.

ORE-SCREENING MACHINE.

No. 825,081.

Specification of Letters Patent.

Patented July 3, 1906

Application filed July 12, 1905. Serial No. 269,327.

To all whom it may concern:

Be it known that I, ALFRED SCHWARZ, a subject of the German Emperor, and a resident of the borough of Manhattan, city, county, and State of New York, have invented 5 certain new and useful Improvements in Ore-Screening Machines, of which the following is a specification.

The present invention relates to a shaking-
10 screen which is capable of general application
to uses to which such devices are adapted,
but which has been designed by me more par-
ticularly for the screening of ores.

The invention will be understood by ref-
15 erence to the accompanying drawings, in
which—

Figure 1 is a side view of the machine,
and Fig. 2 an enlarged detail view of a part
thereof.

20 Similar reference-numerals indicate simi-
lar parts in both the views.

Referring to the drawings, the machine is
supported in a suitable frame comprising
sills 1, uprights 2, and cross-bars or cap-
25 pieces 3. These parts are securely bolted
together to constitute a rigid framework.
The screen comprises two sections, the upper
consisting of a rectangular frame 4 of suitable
timbers, or it may be of metal, bound to-
30 gether by corner-braces 5. A frame 6, usu-
ally of wood, has secured to its lower side a
screen-cloth 7, and said frame rests upon and
is bolted to the frame 4. The lower section
is constructed in a similar manner. It com-
35 prises a rectangular frame 8, the sides and
ends of which are secured together by corner-
braces 9 and supports the frame 10, to which
the cloth 11 is secured. The cloth 7, which
is of wire, is usually from about ten to twenty
40 mesh and the cloth 11 of much finer mesh,
ranging from about twenty to one hundred,
according to the fineness of the ore desired.

The frames 4 and 8 are secured together in
substantially parallel relation by plates 12
45 and 13, bolted thereto, said plates being usu-
ally in the form of castings. There are four
of these plates, two being on the side oppo-
site to that of the view given in the drawings.
The two plates 12 are of less length than that
50 of the plates 13 for the purpose of inclining
the screens forward.

In the lower ends of the plates 12 and 13
are secured studs, on which are mounted

rollers 14, said rollers being preferably
grooved and adapted to rest upon and travel 55
over plates 15, bolted to the sills 1. Said
plates are formed with raised or cam sur-
faces 15', which give a jogging motion to the
screens when the latter are reciprocated lon-
gitudinally by the following means: Secured 60
to the outer sides of plates 12 and 13 are
studs 16 and 17, respectively, to engage slots
in the lower ends of rods 18 and 19, there be-
ing similar rods on the opposite sides of the
machine from that shown. The rods 18 and 65
19 at their upper ends are secured to rock-
shafts 20 and 21, respectively, which shafts
extend across the top of the frame and are
supported in bearings 22 and 23, secured to
the beams 3. Supported in brackets 24, se-
cured to the uprights 2, is a shaft 25, which 70
carries a pulley 26, adapted to receive a belt
from a suitable source of power. On the
shaft 25 is mounted an eccentric 27, the rod
28 of which is connected at its outer end to a 75
cross-bar 29, said bar being secured to and
extending between the two upright rods 18.
Extending transversely of the two screen-sec-
tions is a wall having side pieces 30, the pur-
pose of which is to prevent any material 80
from falling from the upper screen outside
the lower screen. Connected to the frame 6
is a chute 31, leading to a suitable bin to
carry off the oversize from the upper screen,
and 32 is a similar chute leading from the 85
lower screen to carry off the oversize from
the latter.

The operation of the machine will be read-
ily understood from the above description.
By reason of the eccentric connection the 9:
two screens are given a longitudinal recipro-
catory movement and by reason of the cam-
surfaces 15' a vertical jogging movement, the
resultant of these two movements effecting a
complete screening of the ore. The ore to be 95
screened is fed to the upper section 4 by any
suitable means, the material passing through
the cloth 7 falling to the lower section 8.
The material that passes through the cloth
11 is collected in a suitable bin or hopper. 100
The oversize from the sections 4 and 8 are
carried off by the chutes 31 and 32, respec-
tively.

The shaft 25 in practice makes about one
hundred and twenty-five revolutions per 105
minute, and the throw of the eccentric is

2
sufficient to clear the cam-surfaces 15' on each side.

Although I have shown but two sections, it is to be understood that more than that number may be employed. The manner of securing the frames 6 and 10 to the frames 4 and 8, respectively, renders them removable when it is necessary to renew the screen-cloths 7 and 11 or to replace them by a cloth of different mesh.

As shown in the drawings, the screen-sections are inclined forward, thus throwing the lower one to a position slightly in advance of the upper section.

15 What I claim, and desire to secure by Letters Patent, is—

1. A screen comprising a plurality of sections secured together by pairs of plates one pair being of less length than the other and 20 the said sections secured thereto in substantial parallel relation in planes inclined to a horizontal plane, cam-surfaces over which said plates are adapted to be moved, and means for imparting a longitudinal reciprocating movement to the screen-sections.

2. A screen comprising a plurality of sections secured together by pairs of plates, studs carried by said plates, pairs of vertical rods having slotted ends for engaging said 30 studs, rock-shafts to which said rods are secured, means for imparting a vertical jogging movement to said sections, an eccentric-and-pitman connection to said rods, and means for actuating said eccentric.

3. A screen comprising a plurality of sections secured together by pairs of plates, rollers supported by said plates, cam-sur-

faces upon which said rollers rest and upon which they are adapted to be moved, studs carried by said plates, pairs of vertical rods 40 engaging said studs, rock-shafts to which said rods are secured, and means for imparting through said rods a longitudinal reciprocating movement to the screen-sections.

4. In a machine of the character described 45 the combination of a frame, rock-shafts supported thereon, pairs of rods secured to said shafts said rods having their lower ends slotted, a plurality of screen-sections secured together by plates, studs on said plates engaging 50 the slotted ends of said rods, an eccentric-and-pitman connection therefor to one pair of said rods to impart a reciprocating movement to the screen-sections, and means to impart a vertical jogging movement to said 55 sections.

5. A screen comprising a plurality of sections secured together by pairs of plates, one pair being of less length than the other and 60 the said sections secured thereto in substantial parallel relation in planes inclined to a horizontal plane, grooved rollers supported by said plates, cam-surfaces upon which said rollers rest and upon which they are adapted to be moved, and means for imparting a 65 longitudinal reciprocating movement to the screen-sections.

In witness whereof I have signed my name to this specification in the presence of two subscribing witnesses.

ALFRED SCHWARZ.
